TAG-LINE REEL

Roy O. Billings, Milwaukee, Wis.

Application January 21, 1941, Serial No. 375,211

5 Claims. (Cl. 214—146)

This invention relates to improvements in tagline reels.

In the use of cranes for the raising or lowering of buckets, magnets or the like, the latter have a tendency to rotate or swing. This results in a twisting of the operating cables whereby proper operation of the device is hindered. Heretofore, it has been common to utilize taglines for preventing such swinging action of the buckets or magnets carried by the crane. A common arrangement was the use of a counterweight attached to the inner end of the tagline in an endeavor to maintain a proper tension on the tagline. It has been found, however, that a counterweight control does not function properly in all positions of the boom of the crane, and is otherwise objectionable because of the necessity in using therewith a relatively long cable and sheaves. It has also been proposed to utilize a tensioned reel on which the cable is wound. While this type of device will function properly with relatively small buckets or like objects, when a large bucket or the like is employed it is impossible, without the use of a very large expensive spring, to apply sufficient tension to prevent undesired swinging of the bucket.

With the above in mind it is a general object of the present invention to provide a tagline control of the tensioned reel type wherein a relatively small spring of a practical size may be employed, together with means cooperating therewith for automatically maintaining a proper tension regardless of the size of the bucket or device depended from the crane boom.

A more specific object of the invention is to provide a device of the character described wherein means are provided for automatically applying greater resistance than that exerted by a tension spring while a tagline is being paid out, and for automatically relieving this additional resistance when the tagline is being retrieved, thereby eliminating any interference whatsoever with the operation of a coiled spring in rotating the tagline reel in a retrieving direction.

A further object of the invention is to provide an improved tagline reel construction which utilizes a minimum number of parts and which may be arranged in a very compact assembly.

A further object of the invention is to provide a tagline reel construction of the character described having a brake for resisting or placing a drag on the rotating reel shaft, together with manually adjustable means for varying the pressure or drag of the brake.

A further object of the invention is to pro-

vide a brake equipped tagline reel in which the direction of rotation of the reel and shaft is effective to cause automatic application and release of the brake.

5 A further object of the invention is to provide a tagline reel utilizing a relatively large bearing and a minimum number of sheaves whereby undue wear on the bucket cable is eliminated.

10 A further object of the invention is to provide a tagline reel with which a crane boom may be readily equipped at a minimum of expense and with little modification, which is strong and durable, which is automatic in operation, and which is well adapted for the purposes described.

15 With the above and other objects in view, the invention consists of the improved tagline reel and its parts and combinations as set forth in the claims, and all equivalents thereof.

20 In the accompanying drawing in which the same reference characters indicate the same parts in all of the views:

Fig. 1 is a side view of the improved tagline reel mechanism;

25 Fig. 2 is a transverse sectional view taken on line 2—2 of Fig. 1, and on a larger scale;

Fig. 3 is an end view of the tagline reel and associated mechanism;

30 Fig. 4 is a transverse sectional view taken on line 4—4 of Fig. 1; and

Fig. 5 is a fragmentary view of a crane boom and suspended bucket with the cables and tagline reel device attached thereto, said view being on a smaller scale.

35 Referring now more particularly to the drawing it will appear that the invention is shown as being applied to the boom 8 of a crane having a clamshell bucket 9. It should be understood, however, that the invention is applicable to other types of mechanisms where it is desirable to prevent turning or swinging of a depended element. Also, in lieu of a clamshell bucket the crane boom may have a magnet or the like associated therewith. Although only the boom of the

40 crane is illustrated it will be appreciated that the boom is mounted for vertical swinging movement with the carriage of the crane (not shown) being capable of turning horizontally. The bucket 9 is adjustably and movably suspended from the outer end of the boom 8, in a manner to effect raising and lowering movement of the bucket, by an operating cable 10 attached to the bucket and passing over a sheave 11 at the outer end of the boom.

45 A tagline 12 is employed for the purpose of pre-

venting the bucket from swinging or turning during operation thereof. One end of the tagline 12 is attached to a lug on the bucket while the other end portion of the tagline passes between guide pulleys 13 carried by a bracket plate 15. It will be observed that a reel 16 is mounted adjacent the guide pulleys 13. The other end of the tagline 12 is made fast to a portion of the reel 16, in any suitable manner, and turning movements of the reel are adapted to wind or unwind the tagline relative to the grooved periphery of the reel.

The reel 16 is mounted fast on one end portion of a revoluble shaft 17 and this shaft is journaled in suitable bearings 18 and 19. Both of the bearings 18 and 19 project from opposite end portions of a channel iron supporting member 20. The bearing 18 has a depending portion 18' which floats between spaced portions 36 and 37 and is pivotal on a pin 38. With this arrangement, when there is strain on the shaft 17 due to spring tension, the bearing 18 may pivot slightly to cause automatic alinement. The bearing 19, furthermore, is fast with a plate 21, which plate extends adjacent the inner face of the reel 16 and carries the pulley supporting plate 15 by means of arms 22. The channel iron supporting member which carries the reel and associated mechanism is mounted on an intermediate or lower portion of a crane boom 8 in the position shown in Fig. 5. The mounting is accomplished in any convenient manner as by the use of U-bolts which embrace portions of the member 20 and engage transverse struts on the boom.

A coiled spring 23 surrounds the reel shaft 17. One end of the coiled spring is anchored to a lug 24 on a side portion of the bearing 19. The other end of the coiled spring is made fast to a lug 25 on the opposite side of the shaft 17. It will be obvious from the description thus far that as the tagline 12 is paid out and unwound from the reel 16, the reel and shaft 17 will turn in the direction indicated by the arrow in Fig. 2 and due to the anchorage of the opposite ends of the spring 23 the same will be wound up and put under tension. The spring 23, when under tension, normally urges winding of the tagline on the reel and is effective in maintaining tautness in the tagline. However, this arrangement of itself is not sufficient under all conditions to prevent swinging and twisting of the bucket 9. In the present invention the tensioning effect of the spring is augmented by a novel friction brake mechanism adapted to operate on the reel shaft 17.

With particular reference to Figs. 1 and 2 it will be observed that there is mounted fast on the end of the shaft 17 opposite the reel 16, a brake drum 26. This brake drum is surrounded by a strip of flexible brake band 27, formed of any material suitable for the purpose. The brake band 27 is interposed between peripheries of the drum 26 and a substantially O-shaped brake shoe 28. One end of the brake shoe 28 is fixed to a projection 29 on the supporting channel member 20. The other end portion of the brake shoe 28 is flanged outwardly as at 30 and is apertured to receive the shank of an adjusting bolt 31. The upper portion of the shank of the bolt 31 carries a coiled spring 32 which is confined between the brake shoe flange 30 and an upper washer 33. The upper end portion of the bolt 31 has threaded thereon nuts 34 which, when turned downwardly, further compress the spring 32 and cause the same to exert additional pressure on

the flange of the brake shoe, whereby the brake shoe 28 exerts more of a drag or pressure on the brake band 27. The lower end of the bolt 31 is anchored in a flange 35 also supported on the channel iron member 20.

In the operation of the improved tagline reel, when the bucket 9 or other device is lowered, the tagline 12 will pay out and the reel 16 and shaft 17 will turn in the direction indicated by the arrows in Figs. 1 and 2. This action will cause the coiled spring 23 on the shaft 17 to wind up as was heretofore mentioned. This turning movement of the shaft 17 is in a direction to cause the brake band 27 and the brake shoe 28 to compress or bind against the drum 26 and the spring 32 on the bolt 31 is of sufficient strength to exert pressure against the flanged end 30 of the shoe 28 to additionally compress the brake shoe and brake band against the brake drum. The braking mechanism, therefore, exerts a very decided drag on the shaft 17 in addition to the tension exerted by the shaft spring 23. The action of the brake in acting on the shaft is automatic and is occasioned by the direction of rotation of the shaft, it being obvious that when the shaft is being turned in a direction to pay out the tagline, the drag or braking effect on the shaft will be imposed and this will absolutely prevent slack in the main extent of the tagline and will hold the bucket or other mechanism 9 against swaying, swinging, and twisting.

When the cable 10 is operated to raise the bucket 9 the tagline 12 will feed in and wind on the reel 16 which is automatically turned in the proper winding direction by operation of the shaft spring 23. During this stage of operations the automatic brake mechanism again becomes particularly advantageous in that rotation of the shaft 17 in a direction reverse to that shown by the arrow in Fig. 2 causes the brake band 27 and brake shoe 28 to unwrap or release slightly relative to the brake drum 26 with the result that the drag or restraint on the shaft and reel is materially lessened during winding operations of the reel. It may also be stated that the expansive or unwrapping force of the brake shoe 28 is greater, under the latter conditions, than the tension exerted by the spring 32. Also, the condition of the spring 32 may at any time be adjusted by tightening or loosening the nuts 34. From the foregoing description it will appear that the improved tagline reel mechanism is such that the tagline, when being paid out, is under constant restraint and tautness to an extent which will prevent the bucket from undesirably swinging or twisting. The braking arrangement materially augments the shaft spring 23 and is automatic in its operation by placing a desired braking effect and restraint on the shaft in one direction of movement of the shaft, and by releasing said restraint or braking action during the other direction of movement of the shaft. The device is furthermore of simple and novel construction, utilizes a minimum number of parts and is well adapted for the purposes set forth.

What is claimed as the invention is:

1. A tagline reel assembly, comprising an elongated rigid supporting member, bearings at opposite ends of said supporting member, a revoluble shaft having opposite end portions journaled in said bearings, a tension spring coiled about an intermediate portion of the shaft, means securing one end of said spring to one of said bearings, means securing the other end of said spring to a remote portion of the shaft, a tag-

line reel fast on the shaft adjacent said bearing, a hanger rigidly fixed to said bearing and to said supporting member, tagline guide members mounted on said hanger, a friction brake mounted on another portion of the shaft, and means adjustably anchoring portions of said brake directly to said rigid supporting member.

2. In a crane structure, a boom, a material handling bucket or the like movably suspended from said boom, a supporting member connected to said crane structure, a shaft journaled in said supporting member, a reel rigidly carried by said shaft, a tagline having its inner end connected to said reel and having its outer end connected to the bucket or the like to restrain swinging movement of the latter, tension spring means coiled about said shaft and cooperable therewith to normally urge winding of the tagline on the reel, and friction brake means cooperable with said shaft, including a band operable automatically in response to rotation of the shaft in a direction to pay out the tagline to impose friction which supplements the resistance of the spring, and said band being automatically releasable in response to rotation of the shaft in a reverse direction.

3. In a crane structure in combination, a boom, a material handling bucket or the like movably suspended from said boom, a supporting member connected to said crane structure, a reel rotatably mounted on said supporting member, a tagline having its inner end connected to said reel and having its outer end connected to the bucket or the like to restrain swinging movement of the latter, tension spring means cooperable with the reel to normally urge winding of

the tagline thereon, and friction brake means cooperable with the reel and including a band operable automatically in response to rotation of the reel in a direction to pay out the tagline to impose friction which supplements the resistance of the spring, and said band being automatically releasable in response to rotation of the reel in a reverse direction.

4. In a reel construction for use with a tagline attached to a material handling bucket or the like, a support, spaced bearings carried by said support, a shaft journaled in said bearings, a tagline reel rotatable with said shaft, and a spring coiled about said shaft and operatively connected with the shaft and support so as to be wound up when the shaft and reel are rotated in a direction to pay out the tagline, one of said shaft bearings being supported for pivotal movement about an axis which extends at right angles to the axis of the reel shaft whereby the bearing will maintain automatic alinement of the shaft when the latter is subjected to strains caused by spring tension.

5. A tagline reel assembly comprising, an elongated rigid supporting member, bearings at opposite ends of said supporting member, a revoluble shaft extending above and in the same direction as said supporting member and having opposite end portions journaled in said bearings, a tagline reel fast on one end portion of said shaft, a friction brake mounted on another portion of said shaft, and means adjustably anchoring portions of said brake directly to the rigid supporting member.
